J. L. McGAUGH

LUGGAGE CARRIER

Filed June 22, 1926

Inventor
JESSE L. McGAUGH
by *Hagard and Miller*
Attorneys.

Wm. H. Hall

UNITED STATES PATENT OFFICE.

JESSE LEE McGAUGH, OF LOS ANGELES, CALIFORNIA.

LUGGAGE CARRIER.

Application filed June 22, 1926. Serial No. 117,709.

My invention is a luggage carrier for automobiles which may be utilized as a bench or a swing.

An object of my invention is the construction of a luggage carrier which may be attached to the running board of an automobile and be of a foldable type, having legs attached thereto which may be folded when used as a luggage carrier and unfolded to change the luggage carrier into a bench.

A further object of my invention is to have a back for the bench which may be folded against the seat portion when forming the luggage carrier, the arm rest of the bench forming the front and rear ends of the luggage carrier.

My invention will be more readily understood from the following description and drawings, in which;

20. Figure 1 is a perspective view of an automobile with my combined luggage carrier and bench attached thereto;

25. Fig. 2 is a vertical transverse section on the line 2—2 of Fig. 1 in the direction of the arrows;

Fig. 3 is a perspective view of the structure when utilized as a bench;

30. Fig. 4 is a front elevation partly broken away of the bench structure as if taken in the direction of the arrow 4 of Fig. 5;

Fig. 5 is an end elevation of the bench as if taken in the direction of the arrow 5 of Fig. 4.

In the construction shown the automobile 35 is indicated as provided with a running board indicated by the numeral 1 and having front and back fenders 2 and 3. A pair of clamps 4 having upper and lower jaws 5 and 6 and a screw 7 secure upright bars 8 to the running board. These bars engage in straps 40 9 secured to the bottom of the slatted seat construction 10 of the combined luggage carrier and bench.

This seat construction is formed with cross 45 pieces 11 to which are secured the longitudinal slats 12. Legs 13 and 14 are secured to the cross pieces 11 by means of angles 15 which are rigidly bolted to the cross pieces and allow the legs to swivel on pins 16. The 50 leg 13 is attached to one side of the cross piece and the leg 14 to the other end. Swivel catches 17 are secured to the cross pieces 11 and retain the legs in the folded position as shown in Fig. 1.

55. In the unfolded position of the legs, front and back braces 18 and 19 formed of wire

and pivotally connected to the legs engage eyes 20 secured to the front and back slats of the seat construction. End brace bars 21 and 22 formed of wire or rods also engage 60 the eyes 23 at the ends of certain of the slats, thus holding the legs securely braced. When these legs are folded the wires or rods have their ends fit into sockets 24 in the body 65 of the leg construction.

The arm rests 25 are formed of arm bars 26 supported on metal brackets 27, these latter being bent and having the bent end 28 secured to the front and back slats of the seat construction, thereby giving permanent 70 and rigid arm rest constructions. A plate 29 attached to the back of each of the arm rest constructions engages one or more of the slats 30 of the slatted back construction 31. These slats are secured together by cross 75 bars 32. The back is secured to the seat by hinges 33 allowing same to be folded in the position of Figs. 1 or 2 or extended upwardly as shown in Figs. 3, 4 and 5.

From the above construction it will be 80 seen that I have developed a convenient and light luggage carrier which may also be utilized as a bench in the manner above described. When utilized as a luggage carrier the arm rests being held in a rigid position 85 form the front and back elements of the luggage carrier adjacent the front and back fenders 2 and 3. If it is desired to suspend the bench as a swing I provide a series of eyes 34 in the arm bars 26 and a rope or the like may be passed through these eyes suspending the structure above the ground.

It is obvious that my construction may be considerably changed in forming benches of different shapes or other folding articles of 95 camp furniture combined with a luggage carrier. Such changes would be within the spirit of my invention as set forth in the description, drawings and claims.

Having described my invention, what I 100 claim is:

1. A combined bench and luggage carrier comprising a seat structure having folding legs and a folded back hinged to the seat, bars having means to clamp same to the running board of an automobile, and means to secure the seat to said bars.

2. A combined bench and luggage carrier as claimed in claim 1, having arm rests secured to the seat construction, said arm rests 105 forming the front and back ends of the luggage carrier mounted on a running board.

3. A combination luggage carrier and bench comprising in combination cross pieces having seat slats secured thereto, legs pivotally connected to the opposite sides and opposite ends of said cross pieces to fold thereagainst, a back hingedly connected to the seat, arm rests rigidly secured to the seat, having means forming a stop construction to retain the back in the desired position when used as a bench, clamps having upright bars secured thereto, adapted to be attached to a running board of an automobile, and means securing the upright bars to the seat.
4. In a combination luggage carrier and

bench, a plurality of cross pieces having slats forming a seat secured thereto, legs pivotally connected to the opposite ends and opposite sides of the cross pieces and adapted to fold thereagainst, pivoted catches secured to the cross pieces to hold the legs in folded position, clamps having upright bars, said clamps being adapted to be secured to a running board, and straps fitted to the seats engaging said upright bars, holding the bench construction in a vertical position on a running board.

In testimony whereof I have signed my name to this specification.

JESSE LEE McGAUGH.
